UNITED STATES PATENT OFFICE.

CARL HORIX, OF CHICAGO, ILLINOIS.

DESK SET.

Application filed February 10, 1927. Serial No. 167,129.

This invention relates to a desk set for holding articles used in writing in a convenient and accessible position, and has for one of its objects the provision of such a device which shall be attractive in appearance, convenient in use and of improved construction and operation.

A further object is to provide a device of the class named which may be folded into a compact position for storing within the drawers of a desk.

Other objects will appear from the following description.

The invention is exemplified in the combination and arrangement of parts shown in the accompanying drawings and described in the following specification, and it is more particularly pointed out in the appended claims.

20 In the drawings—

Fig. 1 is a vertical sectional view showing one embodiment of the present invention.

Fig. 2 is a top plan view of the device shown in Fig. 1;

25 Fig. 3 is a front elevation of the device shown in Figs. 1 and 2;

Fig. 4 is a side elevation showing a modified form of the invention;

30 Fig. 5 is a top plan view of the form shown in Fig. 4; and

Fig. 6 is a section on line 6—6 of Fig. 5.

Referring first to Figs. 1, 2 and 3, the numeral 10 designates a tray which in the embodiment shown is rectangular in shape and is illustrated as being used for holding sheets of paper 11. The forward wall of the tray is cut out at 12, as illustrated more clearly in Fig. 3, in order to facilitate the removal of the sheets 11 from the tray. The cover for the tray comprises a plate 13 hinged at 14 to the rear end of the tray and having a front section 15 hinged at 16 to the plate 13. The front and side edges of the section 15 are provided with flanges 45 which support a front plate 17 in spaced relation to the section 15 forming a pocket 18. The central portion of the plate 17 is cut away to provide an opening 19 in which interchangeable calendar cards may be inserted, permitting the calendar for the current month to be visible through the opening 19. The front section of the cover 15 is slightly wider than the tray 10 and the side walls of the tray 10 are provided with notches for receiving the forward edge of the cover section 15 to hold the plate 13 in

an inclined upright position, as illustrated in Fig. 1. The plate 17 may be provided with an upwardly rounded portion 20 upon which a monogram may be placed, or which 60 may be used for advertising matter.

Pen sockets 21 are supported on the upper face of the plate 13 and are tapered at their rear ends to form a pocket for the nib of a fountain pen. The sockets are shaped to engage the lower end of the pen barrel, forming a substantially air-tight closure for the pockets in which the nibs are supported, the points of the pen nibs being held in spaced relation to the bottom of the pockets, 65 as illustrated in Fig. 1. A pen socket 21 may be provided at each side of the plate 13 so that the complete set will include two pens which may be used for different colored inks. The pens will be held in position with the nibs down so that the ink in the barrels of the pens will tend to flow downwardly and keep the nibs moist so that the pens will always be ready to write.

The cover may be folded into the position shown in broken lines in Fig. 1, in which position the tray will be closed and the pens will be folded downwardly close to the top of the tray so that the entire set may be placed within the drawer of a desk. The pen sockets 21 may be provided with spacing lugs 22 by which the open ends of the sockets are secured to and spaced slightly from the plate 13. This will give the pens a slightly inclined position when the lid is closed so that the ink will not drain away from the pen points. When the lid is closed, the plates 13 and 15 will be brought into alignment and the extension 20 will fold between the pen sockets 21. If desired, the tray may be provided with an additional socket 23 which may be used for holding a pencil, as illustrated in the drawings.

In the form of the invention shown in Figs. 4, 5 and 6, the tray 10 is dispensed with and a base plate 24 is used to form a support to which a plate 25 is pivoted at 26. In this form of the invention a single socket member 27 is shown in place of the two sockets, as illustrated in Figs. 1 and 2. It will be understood, however, that either form of the invention may be provided with any number of sockets desired. A calendar pocket 28 is hinged to the plate 25 at 29 in a manner similar to that shown in Fig. 1 and the base plate 24 is provided with a stop 100

105

110

30 at its front edge against which the calendar pocket 28 rests to hold the plate 25 and socket 27 in their upright inclined position. Spring tongues 31 are arranged at 5 each side of the plate 24 and have inwardly formed bosses 32 which engage the edges of the calendar pocket 28 when the pocket is folded downwardly in its flat position, as shown in broken lines, and retain the 10 calendar pocket and plate 25 in this position.

face of the other plate for receiving a pen or pencil.

6. A desk article comprising a pair of plates hinged together along adjacent edges, means for holding the opposite edges of said plates in spaced relation, means forming a pocket on the outer face of one of said plates, and a socket member mounted on the outer face of the other of said plates.

7. A desk article comprising a pair of plates hinged together along adjacent edges.

15 While I have shown the plates 15 and 25 provided with pockets for holding calendar sheets, it will be apparent that a large variety of articles may be secured to the outer face of this plate, such as a watch or clock, a thermometer, a barometer, a match safe, or other article which may be useful about a desk.

20 I claim:—

1. A desk set comprising a base member, a support hinged to said base member and having a socket thereon for holding a pen or pencil, and a prop for holding said support in upright position on said base member, said prop being releasable to permit said support to be folded against said base member.

2. A desk set comprising a base, a cover member hinged to said base, a socket member for holding a pen or pencil secured to the top of said cover member and arranged approximately parallel therewith, and means for holding said cover in an open position to support said socket member in upright position.

3. A pen or pencil holder comprising a pair of plates having adjacent edges hinged together, a socket member mounted on one of said plates, and a base for holding the free edges of said plates in spaced relation to each other to support said plates in an angular position relative to each other with said socket member in an upright position.

45 4. A desk article comprising a base, a plate having one edge thereof hinged to said base, a stop on said base arranged in spaced relation to the hinge connection between said base and plate, a second plate 50 having one edge thereof hinged to the free edge of said first-named plate and having the opposite edge thereof arranged to engage said stop to hold the edges of said plates opposite their hinges in spaced relation to each other, and a socket member secured to one of said plates and supported in inclined upright position when said second-named plate engages said stop.

5. A desk article comprising a pair of plates having adjacent edges hinged together, a base for holding the opposite edges of said plates in spaced relation, means for supporting an article on the outer face of one of said plates in position to be visible, and a socket member carried by the outer

6. A desk article comprising a pair of plates hinged together along adjacent edges, means for holding the opposite edges of said plates in spaced relation, means forming a pocket on the outer face of one of said plates, and a socket member mounted on the outer face of the other of said plates.

7. A desk article comprising a pair of 75
plates hinged together along adjacent edges,
a base member hinged to the opposite edge
of one of said plates and having a stop
thereon for engaging the free edge of the
other of said plates to hold said plates in 80
upright angular position, means forming a
pocket on one of said plates having an
opening for exposing an article in said
pocket, and a socket member carried on the
outer face of the other of said plates. 85

8. A desk article comprising a pair of plates hinged together along adjacent edges, a base hinged to the free edge of one of said plates and having a stop thereon for engaging the free edge of the other of said plates to hold said free edges in spaced relation to each other with said plates in inclined upright position, an article holding member on one of said plates, and an extension on the other of said plates projecting past the hinged connection between said plates. 90 95

9. A desk article comprising a base, a lid for said base having a hinged joint extending transversely thereof, one section of said lid being hinged at one edge of said base, a stop for engaging the opposite edge of said lid to hold the sections thereof in angular upright position, and a socket for a writing instrument mounted on one of said lid sections with the open end thereof adjacent the hinged joint between said sections. 100 105

10. A desk article comprising a base, a lid for said base having a hinged joint extending transversely thereof and dividing said lid into two sections, one of said lid sections being hinged at one side of said base, a stop on said base for engaging the free edge of the other of said lid sections, a socket for a writing instrument mounted on one of said lid sections with the open end thereof adjacent the hinged joint between said lid sections, and means forming a pocket having an open side on the other of said lid sections. 110 115 120

11. A desk article comprising a base, a cover for said base having a hinged joint extending transversely thereof and dividing said cover into two sections, one of said sections being hinged to said base, a stop on said base for engaging the free edge of the other of said sections to hold said cover sections in inclined upright position, a pair of sockets for writing instruments disposed at opposite sides of one of said cover sec- 180

tions with the open ends of said sockets adjacent the hinged joint between said sections, and an extension on the other of said cover sections projecting past said hinged joint.

- 5 12. A desk article comprising a base plate, a pair of leg members having adjacent edges hinged together, the base of one of said leg members being hinged to said base plate, a 10 stop on said base plate for engaging the base of the other of said leg members to hold said leg members in inclined upright position, a socket member for receiving a writing instrument mounted on one of said leg members, and a catch for holding said leg members in compacted position against said base.
- 15 13. A desk article comprising a base hav-

ing a lid hinged at one side thereof, said lid having a hinged joint extending transversely thereof parallel to the hinged connection of said lid with said base and dividing said lid into two sections, a socket member mounted on the section of said lid hinged to said base and having its open end disposed adjacent the hinged joint in said lid, means forming a pocket on the upper face of the other section of said lid, and means for engaging the free edge of said last-named section to hold said sections in inclined upright position above said base.

In testimony whereof I have signed my name to this specification on this 8th day of February, A. D. 1927.

CARL HORIX.
